Primary Examiner — John Windmuller*Assistant Examiner* — Steven Czyz(74) *Attorney, Agent, or Firm* — Patents on Demand P.A.; Brian K. Buchheit; Scott M. Garrett(57) **CLAIM**

I claim the ornamental design for a cable tie, as shown and described.

DESCRIPTION

FIG. 1 is a perspective view of a cable tie showing my new design;

FIG. 2 is a left side view of the cable tie of FIG. 1, with the right side view being a mirror image thereof;

FIG. 3 is a front view of the cable tie of FIG. 1;

FIG. 4 is a rear view of the cable tie of FIG. 1;

FIG. 5 is a bottom view of a cable tie of FIG. 1; and,

FIG. 6 is a top view of a cable tie of FIG. 1.

The broken lines depict portions of the article that form no part of the claimed design.

1 Claim, 2 Drawing Sheets(56)
